(57) **CLAIM**

The ornamental design for a skateboard, as shown and described.

DESCRIPTION

FIG. 1 is a perspective view of a skateboard showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a rear side perspective view thereof;

FIG. 9 is an enlarged partial view taken from area 9 shown in FIG. 1;

FIG. 10 is an enlarged partial view taken from area 10 shown in FIG. 8;

FIG. 11 is an enlarged partial view taken from area 11 shown in FIG. 8;

FIG. 12 is an enlarged partial view taken from area 12 shown in FIG. 8; and,

FIG. 13 is an enlarged partial view taken from area 13 shown in FIG. 2.

The shade lines shown in the drawing represent the three-dimensional contour of the design, and are not intended to indicate surface decoration.

The broken-lined circles in FIGS. 1, 2 and 8-13 are included to show enlarged partial views. All other broken lines represent portions of the skateboard that form no part of the claimed design. None of the broken lines form a part of the claim.
